UNITED STATES PATENT OFFICE

162,580

HAT OR SIMILAR ARTICLE

Aaron Rothchild, Flushing, N. Y.

Application October 5, 1950, Serial No. 12,461

Term of patent 3½ years

(Cl. D3—13)

To all whom it may concern:

Be it known that I, Aaron Rothchild, a citizen of the United States, residing at Flushing, in the county of Queens and State of New York, have invented a new, original, and ornamental Design for a Hat or Similar Article, of which the following is a specification, reference being had to the accompanying drawing, forming part thereof.

Fig. 1 is a front elevational view of a hat or similar article, showing my new design.

Fig. 2 is a side elevational view thereof.

Fig. 3 is a top plan view of Fig. 1.

I claim:

The ornamental design for a hat or similar article, substantially as shown.

AARON ROTHCHILD.
